MEANS FOR CUTTING ADITS IN CHALK AND
ALLIED STRATA

James Geary Gardner, Caterham, England

Application November 20, 1942, Serial No. 466,322
In Great Britain June 17, 1942

3 Claims. (Cl. 262—33)

This invention relates to means for cutting adits, channels, galleries or the like in chalk, limestone, compacted clay and kindred earth strata.

When cutting operations are commenced upon a face of chalk or limestone it is normal to employ pneumatic drills or hammers and outline a cavity so that the material enclosed by the cut can be removed. This unfortunately shatters the rock and loosens the formation for some 12 or 18 inches adjoining the cut and if the rock is unstratified and in nodular form, pillars and walls which might otherwise be used to support the roof are useless for such purpose and when galleries are cut for communication passages or caves or rooms excavated for war time shelters, it is frequently necessary to line the parts excavated with brick, and in some cases provide pillars or props in addition.

The object of the present invention is to provide means for cutting the rock instead of shattering it and so avoid the disruption of the confine wall and further to make a cut that is so clean that the wall surface produced has a flat and even surface. With some rocks of the class mentioned, and especially with chalk there is sufficient water latent in the rock and expressed by the percussive cutting operation to form a slurry of the powdered material flowing from the chisel edge and the operation of cutting causes the slurry to flow backwards and relieve the tendency otherwise of the tool to wedge itself in and stick. For rocks that have insufficient latent moisture to form a slurry from the cut face, the tool is grooved or drilled and the cut supplied with water from some suitable external source. In such latter cases water is only required for the initial or first two or three chisel incisions, the space left by the preceding cut or cuts accommodating the swarf material.

The invention consists in means for cutting adits, channels, galleries or passages in chalk, limestone, compacted clay and kindred earth strata, without shattering the formation, whilst providing an even surface and comprises a percussive tool having a long and preferably slightly tapering and relatively thin chisel or jumper portion, said tool being deformed lengthwise intermediate its spigot and chisel portion to bring the penetrating blade out to or beyond the confines of the power driven percussive device adapted to operate said chisel, and to enable it to be driven forward into the rock face and incise by a series of abutting cuts, a predetermined boundary outline, grooves extending from the hilt

to the tip of the blade for the passage of water for slurry the powdered material during the cutting operation. The percussive hammer is provided with a sled for engagement with the wall of the cut, thus aligning the offset blade of the tool with such wall, and the hammer is preferably also provided with a lateral handle for holding the hammer against said wall as the cutting proceeds.

10 10 In order that the invention may be better understood reference is made to the accompanying drawing, wherein a proposed embodiment of the invention is shown and wherein—

15 Fig. 1 is a side elevation of the operating tool.
15 Fig. 2 is a plan of Fig. 1.

Fig. 3 shows the tool in operation cutting an adit or passage in the rock face and leaving an even soffit as cutting takes place.

Fig. 4 is an illustration of the commencement 20 20 of an adit or gallery with a wall partly incised to a predetermined contour, and a portion of the rock material within the incised boundary removed to show the soffit.

Referring to the drawing the cutting chisel or 25 25 jumper A is adapted to be driven by a power driven reciprocating hammer B, see Fig. 3. The tool A has a normal spigot 1, a shank 2, which is bent or deformed at 3 and then straightened and provided with a blade 4, the said blade being 30 30 slightly tapered and provided at its operative end with a square cutting or powdering edge 5 at right angles to the blade 4. A handle 6 is formed integral with, or attached to, the shank 2, and a groove or grooves 7 is or are formed at 35 35 the tool blade shoulder to carry water to the cutting edge. The tool is bent or offset at 3 an amount sufficient to carry the shoulders 8 or hilt of the blade 4 to or outside of the confines of the tool B as shown in Fig. 3.

40 40 The method of use and manner of operation is as follows:

If C represents the rock or quarry face the 45 45 configuration of the adit, gallery or passage 10 (see Fig. 4) is marked out as at 11 and cutting commences, and the entire outline incised as at 12 by penetrating the rock by a series of successive abutting cuts, the rock at floor level being 50 50 also undercut as shown at 13. This cutting operation provides a smooth and even soffit or face 14 as shown in Figs. 3 and 4. The rock material enclosed within the incised boundary can be excavated with a pickaxe, crowbar or other tool, or the device forming the subject of this invention may be used for intercutting as 55 55 shown at 15 in Fig. 3.

If parallel cuts are made as shown at 16, and the rock broken at back as by wedging, the rock may be taken away in rectangular pieces of even size, and used for other purposes. Thus limestone may be excavated in slabs for building, or if chalk be cut, the excavated portions be used for hearthstone or for kindred purposes. At the commencement of cutting, water from any convenient source as from a portable tank 18 may be led by a bendable pipe 19 to the shoulders 3 10 of the tool, and allowed to dribble thereupon or down the face of the rock above the portion being cut. The water so supplied finds its way to the cutting face through the grooves 7 and forms a slurry which exudes at the rock face. After 15 one or a few incisions has or have been made it is generally found that no further water is required, since the powdered rock of successive cuts is driven or falls into the aperture or slit made by the prior cut. Some rocks carry sufficient moisture to render the need of further water unnecessary. In the operation of cutting the tool is driven in up to the hilt or shoulder 8 and is then withdrawn for the next cut. Should the tool stick then the operator seizes the handle 6, and by a combined twisting and withdrawing action jerks the tool backwards and out of its cut, the tapering of the blade assisting this operation.

To assist left handed cutting the power driven hammer B may be provided with a sled 20, and additional grip 21, the sled being pushed against and along the cut wall as driving proceeds.

Should the tool meet flint or stone in its penetration, the tool in the majority of cases will 30

shatter it, but an experienced quarryman will feel the stone and cut upwards or downwards to avoid it, and leave its removal, so as not to injure the surface, until excavation.

5 The chisel or jumper blade 4 is made of a width of face depending upon the power capable of being exercised by a pneumatic or electric percussion tool. The blade length may also vary but an inward cut of 18 to 20 inches is a practical depth for the process of excavation.

The invention is not limited in its scope of application. Thus wells can be bored of any section or underground chambers cut, railroad or canal tunnels can be cut in suitable strata such as chalk with self-supporting roofs having a soffit that appears as if plastered.

I claim:

1. A tool for use in cutting adits and passages in chalk and like materials, comprising a flat chisel-shaped blade having a square cutting edge 20 and of tapered section from hilt to tip, a spigot for attachment to a power percussion hammer, an offset portion intermediate the spigot and the blade, grooves extending from hilt to tip for the passage of water, and a handle extending at right angles to the length of the tool.

2. A tool according to claim 1, in combination with a percussion hammer having a sled for wall engagement and alignment.

3. A tool according to claim 1, in combination with a percussion hammer provided with a sled for wall engagement and alignment, and with an additional lateral handle for left hand cutting.

JAMES GEARY GARDNER.
